UNITED STATES PATENT OFFICE

RUDOLPH W. GLASNER AND FREDRICH J. RODE, OF CHICAGO, ILLINOIS

METAL WORKING PRESS

Application filed January 2, 1930. Serial No. 417,934.

This invention relates in general to metal working presses, particularly adapted, though not necessarily limited in its use with sheet metal die presses in which the work is operated upon between two co-operating dies, one of which is reciprocable toward and away from the other.

In presses of this character different sized dies are employed according to the nature of the work to be performed, and in order to vary the size of the "die space" it is necessary to adjust the ram or the bed of the press, with the result that heretofore the working height of the dies has been varied, in many instances rendering it inconvenient to the operator, with the further result that the efficiency of production is materially interfered with.

Further, it has heretofore been necessary to provide deep pits and foundations in connection with the presses when all of the adjustments have been made in the bed of the press, and the degree of adjustment or variation of the die space has been small.

It is one of the objects of the present invention to overcome these objections and difficulties and to provide in the press a large adjustment of the die space, at the same time maintain the dies at approximately the same working height without increasing the working height of the bed of the press.

To that end improved means are provided whereby the adjustment of the die space will be divided between the bed of the press and the ram or reciprocable slide, with the result that the bed may be positioned at a convenient height for the operator to facilitate the handling of the work and thereby materially increase the efficiency and speed of operation of the press.

A further object is to provide improved means whereby the weight of the ram and the attached die will be counterbalanced, thereby relieving the crank shaft from excessive strain in raising the ram.

To the attainment of these ends and the accomplishment of other new and useful objects as will appear, the invention consists in the features of novelty in substantially the construction, combination and arrangement

of the several parts hereinafter more fully described and claimed and shown in the accompanying drawings illustrating this invention, and in which

Figure 1 is a view partly in elevation, partly in vertical section, partly broken away and with parts removed, of a press of this character constructed in accordance with the principles of this invention and showing the reciprocable ram and die carried thereby in their lowermost positions.

Figure 2 is a detail sectional view taken on line 2—2, Figure 1.

Figure 3 is a detail sectional view taken on line 3—3, Figure 2.

Figure 4 is a sectional view taken on line 4—4, Figure 1.

Figure 5 is a detail sectional view taken on line 5—5, Figure 1.

Figure 6 is a view similar to Figure 4, showing the parts in another position.

Figure 7 is a detail sectional view, taken on line 7—7, Figure 1.

Referring more particularly to the drawings the numeral 10 designates generally the supporting uprights of the press and 11 a crank shaft which is operated from any suitable source of power and in any suitable manner, and the crank shaft 11 is connected by means of links 12 with a slide 13 mounted to move upon suitable guides 14.

In the present form of the invention two of these slides 13 are shown, but it is to be understood that any number of slides suitable for the purpose may be provided, and as the construction and operation of each of the slides and the co-operating and attached parts thereto is the same, the description of one will apply equally as well to them all.

Threaded into the slide 13 are elongated shafts 15 provided with threaded portions 16 and the slides 13 are preferably split as at 17 and the split portions are clamped together by means of fastening bolts 18 and the threads 16 of the shaft 15 engage in threads within the split portions of the slides. The shafts or rods 15 depend below the slide 13 and are journaled by their extremities in suitable bearings 19 in a reciprocable ram 20, the shafts 15 being preferably provided with 100

shoulders 21 and bearing members 22 are threaded into the bearings 19 so as to lock the shafts 15 against longitudinal displacement with respect to the ram. Secured to the shafts 15 for rotation therewith and preferably in close proximity to the ram 20 are gear wheels 23, for a purpose to be hereinafter set forth.

The shafts or rods 15 serve as a means for supporting the ram 20 from the slide 23 and by rotating the shafts 15 the position of the ram 20 may be varied with respect to the slides 13. Any suitable means may be provided for rotating the shafts 15 such as a shaft 24 which is provided with gears 25 on its extremities meshing with the gears 23 and the shaft 24 is journaled in suitable bearings 26.

Secured also to the shaft 24 for rotation therewith is a gear 27 (see particularly Figure 2) which meshes with a gear 28. Connected with the gear 28 for rotation therewith is a worm gear 29 and meshing with the worm gear 29 is a worm 30 arranged within a housing 31 and secured to a shaft 32 for rotation therewith. The shaft 32 is provided with a portion 33 which is angular in cross section and passes loosely through a gear 34 rotatably supported by a bearing 35. The shaft 32 is adapted to be adjusted lengthwise of its diameter and with respect to the gear 34, and during such adjustment the angular portion 33 of the shaft 32 will slide through the gear 34 but the gear will be connected to the shaft 32 for rotation therewith. The gear 34 meshes with a gear 36 on a shaft 37 to which a pulley 38 is connected. A belt 39 passes over the pulley 38 and also over a pulley 40 on the shaft 41 of the motor 42. The motor 42 may be controlled from any suitable point and when the motor is set in operation the shaft 32 will be rotated and this rotary motion will be imparted to the shaft 24 to rotate the shafts 15 and thereby raise or lower the ram 20 with respect to the slides 13, according to the direction of rotation of the shafts 15.

Supported upon the frame of the press is a cylinder 43, one for each of the shafts 15. A piston 44 is reciprocable in the cylinder and connected with the piston is a piston rod 45 which extends through the end of the cylinder and also through a suitable packing or stationary box 46 and is hollow. The hollow portion of the piston rod is threaded as at 47 and the threaded end 16 of the shaft 15 passes into or telescopes with the tubular piston rod 45 and the threads enter into co-operative relation with each other.

A rod or guide 48 is anchored at one end as at 49, preferably to the top of the cylinder 43 and passes through the piston 44 and into the tubular piston rod 45, and is also adapted to pass into the tubular end of the rods or shafts 15. This rod 48 serves the means of

preventing the piston 44 from rotating in the cylinder 43, and to that end the rod or guide 48 is preferably angular in cross section to conform with the opening in the piston 44.

A vent opening 50 is provided in the top 70 of the cylinder 43.

Thus it will be seen that when the shafts 15 are rotated the relative position of the ram 20 and the slides 13 will be varied and also the position of the piston 44 in the cylinder 75 43 and with respect to the slide 13 will be correspondingly varied.

It is the purpose of the cylinders 43 and pistons 44 to counter-balance the weight of the ram 20 and the reciprocating die 51 which is secured to the ram so as to relieve the crank shaft from undue strain necessary to raise the ram and the die. In order to accomplish this counterbalancing effect fluid under the desired pressure is supplied to the cylinders 43 beneath the pistons 44. To that end a pipe 52 has connection with the cylinders beneath the pistons 44 and this pipe in turn has connection with a fluid pressure tank 53, suitably located and which fluid pressure tank 80 receives its supply of fluid from any suitable source through a pipe 54. A pressure regulating valve 55 is provided in the pipe 54 to control and vary the degree of pressure in the cylinders 43.

During the reciprocation of the ram 20 and slide 13 while the press is in operation, the pistons 44 will reciprocate in the cylinders 43, and during the upstroke of the ram and slide the fluid pressure in the container 53 operates upon the lower face of the pistons 44 and will counterbalance the weight of the ram 20 and die 51, any air or fluid on the upper sides of the pistons escaping through the openings 50.

During the descent of the ram the pistons 44 will be lowered in the cylinder 43 and the fluid beneath the pistons 44 will be forced back into the tank or container 53, but as the pressure in the tank 53 is the pressure at which it is desired to maintain the fluid, such fluid will flow back and forth between the cylinders and container during the reciprocatory movement of the pistons 44 in their cylinders.

The bed 56 of the press is also adjustable so as to maintain the working level of the die 57 thereon at the desired elevation.

Any suitable means may be provided for adjusting the bed 56, such as the means disclosed herein, but the specific construction of the bed adjusting means constitutes the subject matter of a separate application, Serial Number 410,317, filed November 29, 1929, and is only described herein in order to give a full and clear understanding of the co-operation of the adjustment of the bed plate with the adjustment of the ram 20.

The bed 56 is supported by means of a cushioning device embodying generally a cham-

ber 58 having tubular members 59 extending through the top 60 thereof. Pistons 61 reciprocate in the tubular members 59 and form supports upon which a pad or pin supporting plate 62 rests. Pins 63 pass loosely through

5 the bed plate 56 and support a work holding member 64 which co-operates with the die 57 and the work 65 is clamped between the die 51 and work holding member 64 to be shaped or formed over the die 57.

10 Depending from the bed plate 56 are toothed members 66 with which locking members 67 having teeth 68 co-operate. These members 68 are adapted to slide in suitable bearings 69 in the frame of the press and are adapted to be moved forwardly and backwardly into and out of co-operative relation with the toothed members 66. To that end cylinders 70 are provided in which pistons 71 operate. The pistons are connected by means of piston rods 72 with the members 67 and fluid is discharged into the cylinders 70 on opposite sides of the pistons 71 through suitable pipes 73-74 which receive fluid under pressure from any suitable source, preferably through a pipe 75. A valve 76 having an operating handle 77 being provided so as to direct the entrance of the fluid and exit of the fluid into the cylinders 70 on one or the other side of the piston 71 therein. Guides 78 are provided for guiding the locking movement of the members 67 and locking nuts or collars 79 are threaded on the guides so as to hold the locking members 67 in the position shown in Figure 1. When the members are in this position the bed 56 will be held against movement by the pressure of the fluid in the chamber 58 and the pin plate or body 62 together with the pistons 61 may then be moved against the resistance pressure created by the fluid in the chamber 58 to yieldingly resist the movement of the work holder 64 under the action of the die 51.

When, however, it is desired to raise the bed 56 of the press the nuts or collars 59 are loosened and fluid is admitted under the piston 71 so as to retract the members 67, thereby causing the teeth 68 to disengage the teeth of the locking member 66. At this time the pressure of the fluid in the chamber 58 will move the pistons 61 with respect to the bed 56 of the press until the body or pin plate 62 engages the bottom of the bed 56. The fluid pressure in the chamber 58 will then cause the bed 56 to be raised. When the proper height is obtained the members 67 are again adjusted and the nuts or collars 79 tightened.

To lower the bed 56 the bed is unlocked by drawing back the members 67 and by exhausting the fluid in the chamber 58 or reducing the pressure of the fluid.

With this improved construction it will be manifest that no matter what size of die 57 is mounted upon the bed plate 56, the bed plate

may be adjusted to any desired height so as to maintain the die at approximately the same working height without materially increasing the height of the bed.

In order to accomplish this it is not only necessary to adjust the bed but it is also necessary to adjust the ram to compensate the variation in the size of the die space. This is accomplished by dividing the adjustment between the ram and the bed, and furthermore by such adjustment it is possible to eliminate or dispense with pits of great depth, and at the same time the working level of the dies will be established and maintained at a convenient height for the operator.

This is quite a desideratum in presses of this character as the variation in the working height of dies seriously handicap the working conditions and work of the operator. By maintaining the working height of the dies at substantially the same height, the rate of production is greatly increased and the operator will be relieved of considerable effort in the lifting of the work and can assume a comfortable position during the operation of the press.

While the preferred form of the invention has been herein shown and described, it is to be understood that various changes may be made in the details of construction and in the combination and arrangement of the several parts, within the scope of the claims, without departing from the spirit of this invention.

What is claimed as new is:

1. A press of the character described embodying an adjustable bed, a ram reciprocable towards and away from the bed with a set throw and providing a die space therebetween, and means for adjusting the ram and the bed with respect to each other to vary the said die space to compensate different size dies, while the working height of the various dies is maintained substantially the same, the last recited means being operable to impart different fixed extents of adjustment to the bed.

2. A press of the character described embodying an adjustable bed, a ram reciprocable towards and away from the bed with a set throw and providing a die space therebetween, and means individual to the ram and the bed for adjusting them one with respect to the other to vary the die space to compensate dies of different sizes while the working height of the various dies is maintained substantially the same, the bed adjusting means being operable to impart different extents of adjustment to the bed.

3. A press of the character described embodying a bed, a reciprocable ram having a set throw, means for adjusting the bed to compensate dies of different sizes and for maintaining the working height of the dies substantially the same, and means for adjust-

ing the ram with respect to the bed to compensate the adjustment of the latter, while the extent of throw of the ram with respect to the bed remains constant.

5. 4. A press of the character described embodying a bed, a reciprocable ram having a set throw, means for adjusting the bed to compensate dies of different sizes and for maintaining the working height of the dies

10 substantially the same, means for adjusting the ram with respect to the bed to compensate the adjustment of the latter, while the extent of throw of the ram with respect to the bed remains constant, and means for

15 counterbalancing the ram.

5. A press of the character described embodying a bed, a reciprocable ram having a set throw, means for adjusting the bed to compensate dies of different sizes and for main-

20 taining the working height of the dies substantially the same, means for adjusting the ram with respect to the bed to compensate the adjustment of the latter, while the extent of throw of the ram with respect to the bed re-

25 mains constant, and fluid pressure means for counterbalancing the ram.

6. A press of the character described embodying a bed, a reciprocable ram having a set throw, means for adjusting the bed to

30 compensate dies of different sizes and for maintaining the working height of the dies substantially the same, means for adjusting the ram with respect to the bed to compensate the adjustment of the latter, while the extent

35 of throw of the ram with respect to the bed remains constant, fluid pressure means for counterbalancing the ram, and means whereby said fluid pressure may be varied.

7. In a press of the character described, an

40 adjustable die supporting bed, a ram reciprocable with a set throw and providing with the bed a die space therebetween, and means for adjusting both the ram and the said bed with relation to each other to vary the size

45 of the said die space while the working height of the die remains substantially the same, the means for adjusting said bed being operable to impart different degrees of adjustment thereto.

50 8. In a press of the character described, an adjustable die supporting bed, a ram reciprocable with a set throw and providing with said bed a die space therebetween, and means for varying the size of the die space while the

55 working height of the die is maintained substantially the same, the means whereby the said die space may be varied being dividable between the said bed and ram, the bed adjusting means being operable to impart different degrees of adjustment thereto.

9. In a press of the character described, an adjustable die supporting bed, a ram reciprocable with a set throw and providing with said bed a die space therebetween, means for

65 varying the size of the die space while the

working height of the die is maintained substantially the same, the means whereby the said die space may be varied being dividable between the said bed and ram, and means for counterbalancing the ram.

10. In a press of the character described, an adjustable die supporting bed, a ram reciprocable with a set throw and providing with said bed a die space therebetween, means for varying the size of the die space while the working height of the die is maintained substantially the same, the means whereby the said die space may be varied being dividable between the said bed and ram, and fluid pressure means for counterbalancing the ram.

11. In a press of the character described, an adjustable die supporting bed, a ram reciprocable with a set throw and providing with said bed a die space therebetween, means for varying the size of the die space while the working height of the die is maintained substantially the same, the means whereby the said die space may be varied being dividable between the said bed and ram, and fluid pres-

80 sure means for counterbalancing the ram, said fluid pressure means embodying a relatively movable cylinder and piston, one of which is connected with the ram and the other connected with a fixed support and means for

85 supplying fluid pressure to the cylinder.

12. In a press of the character described, an adjustable die supporting bed, a ram reciprocable with respect to the bed and having a fixed throw and providing with said bed a die space therebetween, and means for varying the size of said die space while maintaining substantially the same working height of the die, the last said means embodying means for imparting different extents of adjustment to the bed.

13. In a press of the character described, an adjustable die supporting bed, a ram reciprocable with respect to the bed and having a fixed throw and providing with said bed a die space therebetween, and means for varying the size of said die space while maintaining substantially the same working height of the die, the means for varying the said space being dividable between the ram and said bed, the bed adjusting means being operable to impart different degrees of adjustment thereto.

14. In a press of the character described, a die supporting bed, a ram reciprocable with respect to the bed and having a fixed throw and providing with said bed a die space therebetween, means for varying the size of said die space while maintaining substantially the same working height of the die, and means for counterbalancing the ram.

15. In a press of the character described, a ram reciprocable with a set throw, a crank, a slide connected with the crank, rotatable upright rods connected with the ram and having threaded connection with said slide,

means for actuating the rods to vary the set position of the ram with respect to the axis of the crank, and counterbalancing means for the ram connected with said rods.

- 5 16. In a press of the character described, a ram reciprocable with a set throw, a crank, a slide connected with the crank, rotatable upright rods connected with the ram and having threaded connection with said slide,
- 10 means for actuating the rods to vary the set position of the ram with respect to the axis of the crank, and fluid pressure counterbalancing means for the ram connected with said rods.
- 15 17. In a press of the character described, a ram reciprocable with a set throw, a crank, a slide connected with the crank, rotatable upright rods connected with the ram and having threaded connection with said slide,
- 20 20 means for actuating the rods to vary the set position of the ram with respect to the axis of the crank, counterbalancing means for the ram connected with said rods, said counterbalancing means embodying cylinder and
- 25 25 piston elements, one of which is connected with a stationary part of the press and the other with the rod, and means for supplying fluid pressure to the cylinders.

In testimony whereof we have signed our names to this specification, on this 24th day of December, A. D. 1929.

RUDOLPH W. GLASNER.
FREDRICH J. RODE.
